(57) **CLAIM**

The ornamental design for a screwdriver bit, as shown.

DESCRIPTION

FIG. 1 is a perspective view of a screwdriver bit showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is another perspective view thereof, wherein the broken line portions of the screwdriver bit differ from the bit depicted in FIGS. 1 through 7.

The broken lines depict portions of the screwdriver bit in which the design is embodied that are not considered part of the claimed design.
